UNITED STATES PATENT OFFICE.

DAVID HUNTER, OF MINNEAPOLIS, MINNESOTA.

PNEUMATIC DISPATCH-TUBE.

SPECIFICATION forming part of Letters Patent No. 468,419, dated February 9, 1892.

Application filed August 10, 1891. Serial No. 402,227. (No model.)

To all whom it may concern:

Be it known that I, DAVID HUNTER, a citizen of the United States, residing at Minneapolis, in the county of Hennepin and State 5 of Minnesota, have invented certain new and useful Improvements in Pneumatic Dispatch-Tubes; and I do hereby declare the following to be a full, clear, and exact description of the invention, such as will enable others skilled 10 in the art to which it appertains to make and use the same.

My invention is in the nature of an improvement in pneumatic dispatch-tubes of the class shown and described in my pending application 15 entitled "Pneumatic dispatch-tubes," filed May 7, 1891, under Serial No. 391,969.

In my present invention, as in said former application, I employ a system of dispatch-tubes of the ordinary and well-known type and 20 produce a forced draft or current of air there-through by applying a jet of steam to the interior of the discharge or draft pipe of the system and exhaust the combined current of air and steam into an expansion and condensing 25 chamber.

My invention comprises certain improvements in the construction which renders the device more efficient in its work and more perfectly adapts the same to commercial purposes.

These improvements will appear in the following description and be particularly pointed out in the claims.

Reference being made to the accompanying drawings, wherein like letters refer to like parts throughout the several views, Figure 1 is a side elevation of a system of dispatch-tubes equipped with my improvements. Fig. 2 is a longitudinal vertical section of a portion 35 of the draft-pipe in working position, and Fig. 3 is a similar view showing the detachable section of the same removed. Fig. 4 is a section on the line X X' of Fig. 1.

A A' A'' represent the floor-levels of a building.

B B' B'' C C' D E represent the system of pneumatic tubes, and F one of the dispatch-carriers.

G is a detachable section of the draft-pipe 50 B' B'', fitting annular seats G' in annular cap-pieces H H', which are secured to the opposing ends of the two sections of the draft-pipe

B' B''. The cap-pieces H and H' are clamped endwise against the section G to secure the same in position by bolts K and nuts K', which bolts extend through perforations in the projecting annular flanges h of the cap-pieces H and H'.

L is a steam-supply pipe having a detachable nozzle-section L', terminating within the 60 detachable section G and rigidly secured thereto. The sections of the steam-supply pipe are detachably connected by an ordinary valve-nut and screw-thread M M'.

L'' is a hand-valve in the steam-pipe. 65

The section B'' of the draft-tube located in advance of the steam-nozzle is of relatively small diameter as compared with the section B', and the connecting cap-section H' is of conical form. The contracted section dis-charges into an enlarged expansion and condensing chamber N, which connects with an ordinary chimney or stack P. The steam is blown from the nozzle L' through the contracted section B'' with great force, creating 70 a forced draft or current of air in the dispatch-tubes. The steam on its passage into the chamber N is suddenly permitted to expand and then to condense, forming a vacuum, which greatly increases the strength of the 75 current of air in the dispatch-pipes. By the use of the contracted section B'', which the steam and the induced current of air completely fills, any back-current from the discharge end or stack is prevented. 80

It is evident that the section G, containing the steam-nozzle, is readily detachable from the other sections of the draft-pipe by unscrewing the valve-nut, removing the draw-bolts, and springing the section B' backward. 85

The advantage of the detachable section and its connecting cap-plates is that the parts are easily and cheaply made in form for ready application to old or new plants, and ready access is thereby afforded at any time to the 90 parts most likely to get out of order for inspection and repair.

The dispatch-tubes and the receiving-boxes may be made of any suitable material and require no special skill for their construction. 100 The detachable section, its cap-pieces, and the steam-nozzle are the only parts requiring any special fitting. Hence these parts, together with the dispatch carrier or bueket, may be

made and supplied to the trade ready for incorporation into working plants by any ordinary mechanic.

The advantage gained in the action over the 5 construction shown in my former application is a stronger current of air with the use of less steam. In this device, as well as in the former application, the use of the simple steam-jet nozzle is a very important gain over prior constructions, not only in the point of simplicity 10 of structure, but in the point of economy of steam. An extremely small opening is sufficient to give all the draft required on a considerable system of pipes. I have found by 15 actual experience with the construction herein described that a steam-jet nozzle having an opening of three thirty-seconds of an inch is sufficient for a three-floor system of pipes, and that the amount of steam required is so small 20 that it is unappreciable on the steam-gage of the boiler.

It will be understood that the chimney or stack P might of itself serve as the expansion and condensing chamber and serve as the mechanical equivalent of the section or chamber 25 N of the draft-pipe.

What I claim, and desire to secure by Letters Patent of the United States, is as follows:

1. In a pneumatic dispatch system, the com-

bination, with a draft-pipe constructed with a 30 discharge-section of relatively large diameter and with a connecting-section of relatively small diameter, of a steam-supply pipe having its discharge-nozzle inside the draft-pipe, 35 with its discharge in the mouth of the connecting-section, whereby the connecting-section is made to exclude all back-current and the discharge-section is made to afford an expansion and condensing chamber for the steam, substantially as and for the purpose 40 set forth.

2. A fitting for pneumatic dispatch-tubes, comprising a removable section of pipe containing a steam-nozzle provided with means for detachably connecting the same with a 45 steam-supply pipe, a pair of flanged cap-sections fitting the removable section, adapted to be permanently secured to adjacent sections of the draft-pipe, and draw-bolts and nuts for securing the removable section in position, the bolts working through holes in the flanges of said caps, substantially as described. 50

In testimony whereof I affix my signature in presence of two witnesses.

DAVID HUNTER.
